TRAIN ORDER DELIVERER

Aaron B. McFall, Dixon, Ill.

Application October 2, 1936, Serial No. 103,765

4 Claims. (Cl. 258—3)

My invention relates to the delivery of orders and messages to moving trains and has among its objects and advantages the provision of an improved train order deliverer.

5 In the accompanying drawings:

Fig. 1 is a view illustrating my invention showing a message carried thereby;

Fig. 2 is a fragmentary sectional view along the line 2—2 of Fig. 1;

10 Fig. 3 is a sectional view along the line 3—3 of Fig. 1;

Fig. 4 is a sectional view along the line 4—4 of Fig. 1;

15 Fig. 5 is a sectional view along the line 5—5 of Fig. 2;

Fig. 6 is a sectional view along the line 6—6 of Fig. 3;

Fig. 7 is a sectional view along the line 7—7 of Fig. 6;

20 Fig. 8 is a sectional view along the line 8—8 of Fig. 6;

Fig. 9 is a perspective view of a modified form of a message supporting arm; and

25 Fig. 10 is a perspective view of a portion of the message holding string.

In the embodiment selected to illustrate my invention, I make use of a handle 10 including a head 12 which carries two angularly related arms 14 and 16 which support a string 18 holding the 30 message order 20. This string may have its ends tied together so as to form an endless loop, which loop is releasably retained by one of two spring 35 clips 22 fastened to the head 12. A slight concavity 24 is formed in the outer ends of the arms 14 and 16 for string holding purposes.

In operation, the device with the string 18 attached is supported by the operator in such a position as to permit a person on a moving train to pull the string off the device. Because of the 40 angular relation between the arms 14 and 16 and the endless nature of the string 18, the person on the train may easily remove the string by merely hooking the arm therethrough. The spring clips 22 have sufficient tension to hold the string 18 45 with the proper degree of tautness, but the tension is such as to permit the person on the train to remove the string easily with no danger of pulling that person off the train.

In delivering the message, the device is held 50 in a substantially horizontal position with the shorter arm 16 underneath. In making one arm shorter than the other, the free end of the arms may be brought closer to the train with the handle 10 held at a slight angle to the horizontal. 55 This is an important feature in connection with

large engines having such height as to necessitate holding the device at an angle to the horizontal.

Handle 10 is made up of two sections 26 and 28. Section 26 is tubular for slidably receiving the section 28 so as to permit adjustment of the handle for length. A set screw 30 fixedly connects the two sections in various adjusted positions. I provide the outer end of the section 28 with a flange 32 which abuts the end of the section 26 in the shortest adjustment of the handle. 10 In many cases, the section 26 is of sufficient length for message delivering purposes, while in other cases, a longer handle is required, which additional length is easily attained by shifting the section 28.

For packaging and handling purposes under crowded conditions, the arms 14 and 16 may be folded back upon the handle 10, as indicated by dotted lines in Fig. 1. The two angular walls 34 on the head 12 are each provided with a groove 36 of the same cross sectional proportion as the inner ends of the arms 14 and 16 which lie therein. These ends of the arms are releasably housed within the grooves, and may be moved to positions exteriorly of the grooves and pivoted about axes 20 at right angles to the handle 10 to the dotted line position of Fig. 1. In the dotted line position, the arms 14 and 16 lie within recesses 38 in the flange 32, which prevents accidental displacement 25 of the arms.

In Fig. 6, I illustrate the inner ends of the arms 14 and 16 as being tapered at 40, which tapered ends are supported within sockets 42 formed by the lips 44. I prefer to cast the head 12 of light weight material such as aluminum. The head is 30 hollow, as indicated at 46, while each of the walls 34 is provided with a threaded opening 48 for the reception of a sleeve liner 50 having threaded relation therewith and slidably supporting a bolt 52. I provide the sleeve liner 50 with 35 tubular extensions 54 which lend additional bracing and guiding support for the bolts 52.

One slot 56 is provided in each of the arms 14 and 16 for loosely receiving the bolts 52. These slots are of sufficient length to permit the arms 40 to be shifted longitudinally sufficient distances to clear the lips 44 preparatory to pivoting the arms to the dotted line positions of Fig. 1. Upon each bolt 52 I mount a compression spring 58, which spring has abutting relation with a washer 60 and the inner end of the sleeve liner 50. The extensions 54 lie loosely within the springs 58 while the washers 60 have abutting relation with cotter pins 62 passing through openings in 45 the bolts.

The tension of the springs 58 urge the arms 14 and 16 into the grooves 36, but the arms may be pulled out of the grooves against the tension of the springs and pivoted about the bolts 52. 5 Each sleeve liner 60 includes a slot 64 for the reception of a screw driver to facilitate placement or removal of the liner. Washers 66 may be positioned between the heads 68 of the bolts 52 and the arms 14 and 16 to provide additional bearing surface for the arms. The arms may be made of wood.

One of the walls 70 includes an opening 72 normally closed by a plate 74 through the medium of screws 76 having threaded relation with the material of the head 12. In assembling the parts so far described, the sleeve liners 60 are placed in position, after which the bolts 52 are assembled with the arms 14 and 16 and pushed through the sleeve liners. The springs 58 are then placed on the bolts together with the washers 60, after which the cotter pins 62 are attached to the bolts. The opening 72 permits access to the interior of the head for assembling purposes.

25 In many cases it is necessary to deliver train orders under improperly illuminated conditions. To facilitate delivery of messages under such conditions I provide the head 12 with an electric bulb 78 which projects a light beam axially of the handle 10 for illuminating the message 20. Such illumination of the message enables the person on the train to determine the position of the delivery device, thus making it easier to pick up the message. The threaded shank 80 of the bulb 78 is removably retained within a threaded socket 82 terminating in a reflector 84. I provide the head 12 with a hollow extension 86 which houses the bulb and reflector assembly. Screws 88 having threaded relation with the extension 86 pass through openings in the flange 80 comprising material of the reflector 84 for mounting purposes.

The central terminal 92 associated with the bulb 78 is arranged in contact with the pin 94 carried by a body of insulating material 96 attached to the socket 82. To the flange 98 of the pin 94 I weld a conducting wire or rod 100 which has pressure relation with the contact 102 associated with the battery 104. I mount the battery 104 within an opening 106 in the head 12, which opening communicates with a larger bore 108 threaded at 110 for threaded connection with the threaded end 112 of the section 26. New batteries may be substituted by merely unscrewing the section 26 from the head 12. A resilient finger 114 is rotatably mounted on a screw 116 having threaded relation with the head 12. This finger may be rotated about the screw 116 to a position clear of the battery for placement and removal purposes, but when pivoted to a position underneath the battery, the latter will be supported in a position illustrated in Fig. 6.

A switch 118 is arranged in operative relation with a second battery contact 120 for energizing the bulb 78. In Fig. 8, the switch 118 includes a shaft 122 rotatably mounted within a liner 124 anchored in a threaded opening in one of the walls 70. I cut away the switch 118 at 126 so that in one position of adjustment, the switch will be arranged in spaced relation with the contact 120, but in the other position of adjustment, the switch will be arranged in pressure relation with the contact for closing the circuit. I provide the shaft 122 with a knurled knob 128 75 for turning purposes.

I enclose the conductor 100 within an insulated shell 130 which fits snugly within an opening in a cross member 132 carried by the walls 70. Because of the shell 130, the conductor 100 is insulated from the head but is supported thereby. 5

The reflector 84 possesses conducting properties and is arranged in electrical conducting relation with the head 12. Switch 126 is also arranged in electrical conducting relation with the head 12. Thus, the circuit through the bulb 78 10 is closed when the switch 118 is moved into contact with the battery contact 120. I prefer to provide the switch 126 with flat sides 134 which have pressure relation with the contact 120 so that the position of the switch may be determined by a sense of touch. 15

In Fig. 9, I illustrate a slightly different form of arm corresponding to the arms 14 and 16 in which the wood or rattan rod 136 is secured within a socket 138 terminating in a reach 140 shaped 20 to lie within one of the grooves 36 in the same way as the arms 14 and 16. Reach 140 is provided with a slot 142 and is tapered at 144 in the same manner as the arms 14 and 16. A pin or screw 146 may be used for securing the rod 136 25 within the socket.

In Figs. 6 and 10, I illustrate the manner in which the order 20 may be connected with the string 18. In Fig. 6, the message 20 is folded a number of times and is folded diagonally at 148. 30 The string 18 is doubled back upon itself and the doubled part folded back upon itself in the form of a loop to provide a loop 150 through which the order is inserted. Because of the folded condition of the order, the loop 150 may be drawn 35 tightly thereabout, and the order will withstand pulling forces transmitted to the string during and after connection with the arms 14 and 16 and the clip 22.

In Fig. 10, each end of the string is knotted 40 about the other end, as at 152, to provide an Englishman's tie. The order is inserted at 154. Knots 152 may be drawn closer together by pulling on the reaches 156. As the knots are drawn closer together, the message will be pressed between the knots and the reaches 158. The latter reaches transmit sufficient pressure to the folded order to balance collapsing forces transmitted thereto by the knots 152. The tie illustrated in Fig. 10 resists collapsing of the order to a degree 50 which permits the string to be connected with the deliverer under the necessary degree of tautness. The order or message may be released from the tie by merely pulling the ends 154 simultaneously in opposite directions. 55

With the clips 22 attached to the head 12 on opposite sides thereof, the string 18 may be so connected with the deliverer and one of the clips as to permit the direction of pull exerted on the string 18 to be away from the deliverer regardless of the direction of travel of the train. The arms 14 and 16 embody sufficient flexibility to permit the string to be pulled easily out of the concavities 24. I have arranged the resilient mounting for the arms 14 and 16 within the head 12 so as to provide a compact arrangement of the parts and one in which the head affords protection for the mounting. At the same time, the resilient mounting is housed within the head in such a 70 manner as to eliminate projections beyond the head on which the string 18 might catch.

Without further elaboration, the foregoing will so fully explain my invention that others may, by applying current knowledge, readily adapt the 75

same for use under various conditions of service.

I claim:

1. A device of the type described comprising a telescopic handle provided with a head having 5 grooves, string supporting arms having their inner ends lying within said grooves, said grooves terminating in sockets for the reception of the inner ends of the arms, and resilient means urging the arms into the grooves.

10 2. A device of the type described comprising a handle having a head provided with grooves, string supporting arms having their inner ends lying within said grooves and provided with slots, said grooves terminating in sockets for supporting 15 the inner ends of the arms, bolts connected with the head and extending through said slots, and springs mounted on said bolts for urging the arms into said grooves, said slots being of such length to permit the arms to be moved in the 20 clear of said sockets, said springs permitting the arms to be moved in the clear of said grooves and rotated on the bolts.

25 3. A device of the type described comprising a handle, a pair of string supporting arms, pivot means for connecting the inner ends of the string

supporting arms with one end of the handle, means cooperable on the inner ends of said string supporting arms and the said one end of the handle for restraining the arms from accidental pivotal movement, resilient mounting for said pivot means so constructed and arranged as to permit the pivoted ends of the string supporting arms to be moved out of restraining relation with said second named means, to permit the arms to be folded back upon the handle. 10

4. A device of the type described comprising a handle including a hollow head, a pair of string supporting arms, means on said head for holding the string supporting arms in divergent relation, pivots for pivotally connecting the arms 15 with said head, resilient means located inside the hollow head and cooperable on said pivots for yieldably holding the arms in connected relation with said first named means, said pivots being movable longitudinally of their axes, to bring the 20 arms in the clear of said first named means, to permit the arms to be folded back upon the handle. 20
